Primary Examiner—T. Chase Nelson*Assistant Examiner*—Karen Acker(74) *Attorney, Agent, or Firm*—Perkins Coie LLP(57) **CLAIM**

The ornamental design for the firebox surround, as shown and described.

DESCRIPTION

FIG. 1 is an isometric view of the firebox surround showing our new design.

FIG. 2 is a front elevational view.

FIG. 3 is a rear elevational view.

FIG. 4 is a right-side elevational view. The left-side elevational view is substantially the same as the right-side elevational view.

FIG. 5 is a top plan view; and,

FIG. 6 is a bottom plan view.

Any broken lines in the drawings are for illustrative purposes only and form no part of the claimed design.
